UNITED STATES PATENT OFFICE.

WESLEY W. GARY, OF BOSTON, MASSACHUSETTS.

ELECTRIC RAILROAD-SIGNAL.

SPECIFICATION forming part of Letters Patent No. 240,692, dated April 26, 1881.

Application filed February 6, 1880.

To all whom it may concern:

Be it known that I, WESLEY WARD GARY, of Boston, in the county of Suffolk and State of Massachusetts, have invented certain Improvements in Electric Railroad-Signals, of which the following is a specification.

The object of my invention is to produce an automatic electric signal to give warning of the approach of a railway-train; and to this end it consists in the peculiar construction and arrangement of devices hereinafter described.

Figure 1 represents a perspective view of my apparatus arranged in connection with the railroad-track. Fig. 2 represents a top-plan view of the generator or magneto-electric apparatus; Fig. 3, a side elevation of the same; Fig. 4, a top-plan view of the alarm; Fig. 5, a side elevation of the same.

A represents an ordinary railway-track; B, an electric conducting-wire extending along the side of the track; C, the bell-alarm connected with one end of the conductor B, and D the magneto-generator connected with the opposite end of the same.

The alarm is located at the side of the track upon an elevated post, or otherwise, and the conductor preferably arranged upon insulated support, while the generator is located near the track. The generator consists, as shown, of a fixed permanent magnet, *a*, and an armature provided with an insulated coil or helix, *c*, and arranged to vibrate to and from the end of the magnet, the helix forming a part of the circuit through conductor B.

The armature is mounted on one end of a vibrating arm or lever, *d*, secured to a rock-shaft, *e*, which latter is extended beneath one of the rails of the track, and provided with an arm, *f*, extending in the opposite direction from arm *d*. The wheels of the train passing in succession over arm *f* depress the same, and thereby rock the shaft *e*, thereby causing arm *d* to elevate the armature away from the magnet. After the passage of each wheel the magnet again descends by gravity before the action of the next wheel upon the arm *f*. In this way the armature is given a rapid vibratory motion in relation to the magnet, inducing a series of strong electric currents or impulses through the circuit B. While the action of gravity is sufficient in ordinary cases to depress the ar-

mature, a spring, *g*, may be used in connection therewith, if desired.

Passing, now, to the alarm C, it will be seen to consist of two permanent magnets, *h* and *i*, having their opposite poles arranged facing each other, and an intermediate armature, *k*, provided with a helix, *l*, and sustained by a spring-arm, *m*, so that it may vibrate rapidly between the two magnets. A branch or prolongation of the arm *m* carries a hammer or striker arranged to act upon a bell, *n*. The spring *m* is so arranged that it holds the armature normally in an intermediate position between the two magnets, free from contact therewith. The electric currents or impulses transmitted through the circuit B serve to magnetize and demagnetize the armature *k* and to change its polarity rapidly and frequently, the result of which is that the armature is caused to vibrate rapidly between the two magnets, so that the striker acts strongly and rapidly upon the bell, thus giving notice at one end of the line that an approaching train has arrived at the opposite end.

I am aware that electric signals have been released by means of magneto-electric generators actuated by the wheels of a passing train, the signal being designed to give warning to a train advancing behind another.

I am also aware that magneto-generators embracing the combination of a permanent magnet and a vibratory armature and helix are old, and I lay no claim thereto.

I do not claim, broadly, herein the combination of an electrically-driven bell and a magneto-generator actuated by passing trains; nor do I claim herein a bell-alarm wherein an electro-magnet operating a striker is arranged to vibrate between two permanent magnets, as said features will be made the subject-matter of a separate application.

Having thus described my invention, what I claim is—

1. In an organized alarm-signal for railroads, the combination of a bell-alarm consisting of two permanent magnets and an intermediate armature and helix with striker attached, the electric conductor extended from the alarm to an advanced point by the track, and a magneto-generator located at the last-named point and consisting of a fixed magnet, a gravitat-

ing-armature and helix attached to a rock-shaft having an arm arranged to be depressed by the wheels of the passing train.

2. In combination with the magnets *h* and *i* and the intermediate electro-magnet with striker attached, the generator consisting of the permanent magnet, the electro-magnet *b c*, and the arm *f*, arranged to be operated by the wheels of the passing train.
- 10 3. In an automatic railroad-signal, the combination of a signaling-instrument embracing two permanent magnets and an intermediate vibratory electro-magnet, an electric conductor extending thence to a distant point at the side
15 of a railway-track to a magneto-generator embracing an electro-magnet, and a permanent magnet and mechanism, substantially such as

shown, for vibrating one of said members with relation to the other under the action of each of the passing car-wheels.

- 20 4. In an automatic railway-signal, the combination of a vibratory magneto-generator, such as described and shown, means whereby each car-wheel is caused to impart a movement to the generator, and a signaling-instrument electrically connected with the generator, and embracing two permanent magnets and an intermediate electro-magnet embraced in the circuit.

WESLEY WARD GARY.
